DESIGN FOR A HANDKERCHIEF SLIDE

Lenus J. Hostetter, Oakland, Calif.

Application April 3, 1939, Serial No. 83,995

Term of patent 14 years

To all whom it may concern:

Be it known that I, Lenus J. Hostetter, a citizen of the United States, residing at Oakland, in the county of Alameda and State of California, have invented a new, original, and ornamental Design for a Handkerchief Slide, of which the following is a specification, reference being had to the accompanying drawing, forming part thereof.

Fig. 1 is a front elevational view of a handkerchief slide showing my new design.

Fig. 2 is an edge view; and

Fig. 3 is a rear elevational view thereof.

I claim:

The ornamental design for a handkerchief slide, substantially as shown.

LENUS J. HOSTETTER.
